UNITED STATES PATENT OFFICE

153,064

DESIGN FOR A GAS PRESSURE REGULATOR

George L. Hammon, Berkeley, Calif., assignor to
National Welding Equipment Co., San Fran-
cisco, Calif., a corporation of California

Application March 11, 1947, Serial No. 137,520

Term of patent 14 years

(Cl. D78—1)

To all whom it may concern:

Be it known that I, George L. Hammon, a citizen of the United States of America, residing at the city of Berkeley, in the county of Alameda and State of California, have invented a new, original, and ornamental Design for a Gas Pressure Regulator, of which the following is a specification, reference being had to the accompanying drawing, forming part thereof.

Fig. 1 is a perspective view of a gas pressure regulator, showing my new design;

Fig. 2 is a side view of the same regulator, looking at Fig. 1 from the left;

Fig. 3 is another side view, looking at Fig. 1 from the right;

Fig. 4 is a front view thereof; and

Fig. 5 is a back view thereof.

The parts shown in dotted lines in Fig. 1 are omitted in the other views for convenience of illustration. The dominant features of the design reside in the portion shown in full lines.

I claim:

The ornamental design for a gas pressure regulator, as shown and described.

GEORGE L. HAMMON.
